UNITED STATES PATENT OFFICE.

WERNER BEUTEL, OF BRIDGEPORT, CONNECTICUT.

AUTOMATIC TRAIN-STOP.

1,110,739.

Specification of Letters Patent. Patented Sept. 15, 1914.

Application filed March 1, 1913. Serial No. 751,476.

To all whom it may concern:

Be it known that I, WERNER BEUTEL, a subject of the Emperor of Germany, and resident of Bridgeport, in the county of Fairfield and State of Connecticut, have invented certain new and useful Improvements in Automatic Train-Stops, of which the following is a specification.

My invention relates to improvements in automatic railway locomotive stops and it belongs to that particular class of devices of this kind wherein air pressure automatic mechanisms are employed for shutting off the steam from the locomotive boiler to the engine.

The invention is designed to be used in connection with most any of the practical forms of signal devices now in use, and with this in view is arranged to be connected therewith so as to produce an automatic stoppage of the engine and train when the signal is set against the same, but is so constructed and arranged as to avoid being operated when such signals are not set against the train.

The further object of the invention is to provide a device which will be positively operated whether the train be going in a forward or backward direction or if going in either direction upon a single track, and so as to prevent the train from running past a danger signal.

Upon the accompanying two sheets of drawings forming a part of this specification similar characters of reference will be found to designate like or corresponding parts throughout the several figures and of which,

Figure 1, shows, by dotted lines, a side elevation of a locomotive and track fitted with my improved automatic stop mechanism, the said stop mechanism being shown in full lines, and mounted in the cab and upon the rear portion of the locomotive. Fig. 2, is an enlarged sectional elevation of a cylinder and its extended piston shown in Fig. 1, for engaging the contact member mounted upon the railway track. Fig. 3, is a sectional elevation taken at a right angle to and further illustrating the mechanism shown in Fig. 2. Fig. 4, is a side view of the contact device that is connected with and operated by the signals, and which is attached to the road bed so as to be engaged or not by the automatic operating mecha-

nism carried by the locomotive. Fig. 5, is a plan view of the said contact mechanism shown in Fig. 4. Fig. 6, shows an enlarged sectional elevation of the means for automatically operating the steam throttle lever within the locomotive cab and the air valve. Fig. 7, is a central vertical sectional view through the air brake valve indicated by 59 and as seen from the opposite side from that shown in Fig. 1. Fig. 8, is an enlarged side view of the valve mechanism shown in Figs. 1 and 6 and which is automatically released and permitted to operate with the striking of the piston arm shown in Figs. 1, 2 and 3. Fig. 9, is a top plan view of the mechanism shown in Fig. 8, and, Fig. 10, shows a plan view of the short section of a railway track fitted with such of my improved mechanism as is mounted upon the track and road bed and connected with the signals.

Referring first to Fig. 10 it will be seen that the contacting devices 11 are mounted upon the road bed adjacent to the track 12 and are designed to be engaged by the automatic appliances carried by the locomotive, and that contacting devices are connected by wires and levers with the signals so as to be operated in conjunction therewith. The particular form of signal 13 shown in this figure is mounted upon a post and is known as a semaphore, yet it will be obviously apparent that the connections may be made with any movable form of signal device, as for instance a movable ground or lamp signal mounted upon the road bed. These contacting devices 12 are used in pairs for single track roads, one being arranged on each side of the track, the two said devices are connected together by wires 14 which in turn connect with the operating arms of the said contacting device and the pivotal lever 15 to which the wire 16 from the signal 13 is attached. These contacting devices are more clearly shown in larger views in Figs. 4 and 5 and as will be seen include a slide which may be shoved forth in line with the travel of the piston arm carried by the locomotive so as to insure the same striking at such times as when the signals are set against the train. In detail this contacting device includes a base frame 17 that may be bolted to one of the ties of the track and is provided with a transverse way in which the slide 18 is mounted. This slide is provided with a pin 19

19 that extends up through a slot in an arm 20 mounted upon a rocker shaft 21 and bearing a second arm 22 for the connection of the before mentioned wires 14. When the 5 signal is set against the train the connected wires are so adjusted as to operate the arms 22 and slide 18 and to shove the slide in toward the rails to a projected or extended position and in line with the travel of the 10 piston arm 23 of the trip mechanism carried by the locomotive. On the other hand when the signals are set to indicate a clear track this same engaging slide is drawn back out of the way to permit a free passage 15 of the piston arm therewith.

15 The automatic mechanism carried by the locomotive which is operated by engagement with the before mentioned contacting devices is mounted in part in the locomotive 20 cab and in part immediately thereunder. It thus serves to be more directly and conveniently connected with the throttle lever 24 of the locomotive which serves to operate the main steam valve (not shown) 25 controlling the supply of steam from the boiler to the locomotive cylinder. This lever 24 is designed to be manually operated in the usual way and also to be operated through said lever by the air pressure 30 carried in the compressed air tank 26 of the locomotive, through the medium of cylinders, pistons, springs and trip mechanism that are connected with and operated by the before mentioned piston arm carried 35 by the locomotive and which serves to engage the before mentioned slide 18. A link 27 is pivotally connected to the piston rod 28 and is made to engage the before mentioned operating lever 24 through the medium 40 of a pawl and rack connection as is clearly shown in Fig. 6. The piston rod 28 extends out from and is connected with the piston 29 mounted within the compressed air cylinder 30 whose ports 31 and 31^b lead 45 to it from an adjoining chamber 32. This chamber 32 has mounted within it a balanced reciprocating slide valve 33 that is provided with a longitudinal port 33^a extending therethrough and has a stem projecting 50 out from either end. One of these stems 36 is provided with a spring 35 that normally tends to draw the said slide valve to the right as shown in dotted lines in Fig. 6 to allow a free passage of air out 55 through the pipe 31^b from the said chamber and thence through the exhaust port 31^a when the parts are set in their position. The stem 37 extended from the opposite end of the slide valve is supported in an 60 extended bracket 38 and has connected to its outer end an operating lever 39 which is pivoted to the before mentioned bracket 38. A beveled edged disk 40 is secured upon the stem 37 and serves to be engaged by a bell 65 crank lever 41 that is pivotally connected

to the said bracket 38. A spring 42 serves to normally hold the tooth 43 of the arm 41 in engagement with the edge of the said disk 40. This mechanism thus serves to prevent a movement of the said balanced slide valve and its stems to the right from the action of its spring 35. The said parts are set in the position shown in Fig. 6 when the locomotive is started by the operation of the lever 39 which draws the rod 37 forward as shown until the disk 40 is engaged by the tooth 43 of the bell crank lever which tends to hold the parts in said position until released. This condition obviously leaves the port 31 in communication 80 with the exhaust 31^a and the other port 31^b uncovered to the compressed air pressure, the said air pressure thus also fills both ends of the chamber 32, and forming an equal air pressure on both ends of the slide 85 valve, when the disk 40 and its stem 37 are automatically released as will later be explained, the spring 35 draws the slide valve 33 to the right (see dotted lines), so as to connect the port 31^b with the exhaust 31^a 90 and to permit a free flow of air through the ports 33^a and 31 back of the slide valve 29 so as to drive the same back in a way to operate the lever 24 and to close its connected valves. This line of mechanism is 95 operated through a chain connection 44 which passes down over the idler rollers 45 shown in Fig. 1 and is connected with the spring actuated rod 46 supported in a frame 47. This spring 48 serves to retain 100 the rod and its connecting links 49 in an uppermost position thereby relieving the bell crank lever from any function of supporting the same. The said links 49 are provided with slots 50 in their lower ends which 105 slidably connect the said links with pins 51 carried in the oppositely disposed arms 52 of the air cylinder 53. This cylinder, see Figs. 2 and 3, is pivotally hung in a bracket 54 hung in any suitable manner to 110 the frame work of the locomotive and through the pivotal journal portion 55 of the said cylinder is provided an air passage 56 that is connected by a pipe 57 with the compressed air tank 26. Ports 58 of the 115 cylinder connect this passage 56 with the upper end of the cylinder 53 so as to convey the air from the said tank to the upper end of the cylinders at such times as when the valve 59 is opened.

120 A piston 60 is mounted to reciprocate in the cylinder 53 and is provided with a depending piston arm 61 that extends down and out of the cylinder more or less according to the action of its spring 62, and whether or not the air is turned in said cylinder. This piston arm as before stated is extended at the proper time for engagement with the slide 18 of the contacting device mounted upon the track bed. The slide 130

as before stated is intended to be extended only when the signals are set against the train.

The piston arm 61 is normally extended when the train is in motion by reason of the air pressure and against the action of the spring 62, but is designed to be lifted by said spring when the air pressure is cut off. The air valve 59, before mentioned, as will be seen is directly connected by a link 63 with the throttle lever 24 of the locomotive and is thus set in an open position when the throttle lever is drawn back as seen in Figs. 1 and 6 to open the main steam valve (not shown). The said valve 59 upon the other hand is closed and the air pressure not only cut off from the cylinder 53 but the air contained therein is allowed to escape through the ports 59^a and 59^b when the throttle valve lever 24 is shoved forward to reduce or stop the speed of the locomotive, thereby permitting the spring in the cylinder 53 to raise the piston arm 61. On the other hand, if the engineer neglects to operate the throttle lever 24 when the signals are set against him, the piston arm 61 will be extended for engagement with the slide 18 which has previously been shoved forward in the path of the arm by the setting of the track signal 13.

Having thus described my invention what I claim and desire to secure by Letters Patent is:—

1. In an automatic railway locomotive stop, the combination with a suitable contacting device secured to a road bed, of a cylinder pivotally connected to the locomotive and having oppositely disposed arms, a piston arm mounted in the cylinder to engage said contacting device and adapted to swing with the cylinder to pass the contact, air pressure connections with the cylinder for holding said piston arm extended for engagement with the contacting device, a spring for withdrawing the piston arm when the air pressure is removed and mechanism connected with the oppositely disposed arms of the cylinder for removing said air pressure.

2. In an automatic railway locomotive stop, the combination of a movable contacting device secured to a road bed, of an air cylinder pivotally attached to the locomotive and adapted to be swung forward and backward, a piston and arm mounted in the cylinder to engage said contacting device and adapted to swing with the cylinder, pressure actuated means for holding said arm extended for engagement with the contacting device, means for retracting the arm

when the air pressure is removed, and mechanism connected with the swinging cylinder for removing said air pressure.

3. An automatic railway locomotive stop, comprising a suitable contacting device secured to a road bed, an air pressure cylinder pivotally hung to the locomotive, an arm mounted in the cylinder and adapted to engage said contacting device and adapted to swing rearward with the cylinder to pass the contact, air pressure actuated means for holding said arm extended for engagement with the contacting device, a spring actuated slide valve for controlling said pressure actuated means, means for retracting the arm when the air pressure is removed, and mechanism connected with the swinging arm to control the slide valve for relieving said air pressure.

4. In an automatic railway locomotive stop, the combination with a suitable contacting device secured to a road bed, of a throttle valve lever, a spring actuated slide valve for controlling the operation of the throttle valve lever, a pivotal arm carried by the locomotive to engage said contacting device and adapted to swing back to pass the contact, a latch for holding the slide valve in inoperative position, connections with said swinging arm to release the slide valve, air pressure actuated means for holding said arm extended for engagement with the contacting device, and means for retracting the arm when the air pressure is removed by engagement with and the operation of the arm.

5. In an automatic railway locomotive stop, the combination with a suitable contacting device secured to a road bed, of a throttle valve lever, an air pressure operating means for operating the throttle lever, a spring actuated slide valve for controlling said air pressure operating means, a cylinder pivoted to swing upon the locomotive, an arm carried by the cylinder to engage said contacting device and adapted to swing with the cylinder to pass the stop, a connection between the said cylinder and the spring actuated slide valve to release the latter, air pressure actuated means for holding said arm extended for engagement with the contacting device, and means for retracting the arm when the air pressure is removed.

Signed at Bridgeport, in the county of Fairfield and State of Connecticut, this 20th day of February, A. D. 1913.

WERNER BEUTEL.
